UNITED STATES PATENT OFFICE

2,670,091

CRATE UNLOADER

Russell W. Sinks, Sidney, Ohio

Application June 30, 1950, Serial No. 171,317

6 Claims. (Cl. 214—307)

1

The present invention relates to a crate unloader and particularly to an unloader for crates of cans. Canned commodities are usually cooked in the cans in which they are sold. After a commodity is sealed in cans, the cans are placed in a crate and the crate in turn is placed in a boiler to cook the commodity. After the cooking, a paper label is wrapped around each can. During the processing of the commodity, the cans are disposed haphazardly in the crate. In modern packing plants, a can unscrambler is used. This unscrambler rights all the cans so that they lie or set uniformly for delivery to the can labeling machine. The present invention is primarily directed to a machine for inverting the crate containing the cans and for limiting the flow of cans from the inverted crate to such rate that the unloading is synchronized to the capacity of the can unscrambling machine.

In carrying out the present invention, there is provided a main frame which forms a station for receiving open top crates of cans. The main frame includes a crate carrying frame which is movable over the receiving station and has means for engaging the crates to lift the same. The crate carrying frame includes a door for closing the open top of the crate. Mechanism is provided for moving the crate carrying frame, with the crate attached, and for inverting the carrying frame and the crate. Mechanism is also provided for slowly opening the door, when the carrying frame and crate are inverted, whereby the rate of flow of cans from the crate is controlled.

A conveyor, in the form of an endless belt, receives the cans, which are unloaded from the crate, and conveys them to the can unscrambling machine. This conveyor is disposed below the crate. A slide for the cans is disposed below the crate and above the conveyor and is moved along the bottom of the crate as the door, for the crate, is being opened.

Further objects and advantages of the present invention will be apparent from the following description, reference being had to the accompanying drawings wherein a preferred form of embodiment of the invention is clearly shown.

In the drawings:

Fig. 1 is a front view of the crate unloader, showing the position of the crate in the receiving station and showing the crate carrying frame in position to lift the crate;

Fig. 2 is an end view looking in the direction of arrow 2 in Fig. 1;

Fig. 3 is a fragmentary view, similar to Fig. 1,

2

but partly in section and showing the carrying frame and crate carried thereby in a position midway of the receiving and unloading stations;

Fig. 4 is a fragmentary view, similar to Fig. 1, but partly in section and showing the carrying frame and crate at the unloading station, and showing the door for the crate in closed position; parts of the machine are shown in section;

Fig. 5 is a view similar to Fig. 4 but showing the door partly open;

Fig. 6 is a sectional view, on a larger scale, the section being taken on line 6—6 of Fig. 5;

Fig. 7 is a sectional view, on the same scale as Fig. 6, the section being taken on line 7—7 of Fig. 5;

Fig. 8 is a view, on the same scale as Fig. 6, looking in the direction of arrows 8—8 of Fig. 7;

Fig. 9 is a sectional view, on the same scale as Fig. 6, the section being taken on line 9—9 of Fig. 1; and

Fig. 10 is a fragmentary view, partly in section, the view being taken on line 10—10 of Fig. 5.

Referring generally to the drawings, there is shown a main frame 20 which includes a base 21 and oppositely disposed uprights 22, secured to and extending upwardly, the latter being secured to the base and extending upwardly substantially centrally of the base, as viewed in Fig. 1. These uprights 22 are braced by the diagonally disposed braces 24, which in turn are braced by diagonally disposed braces 25.

The space to the left of uprights 22 and above the base 21 will be referred to as a receiving station 27. A plurality of rearwardly extending tracks 28, as viewed in Fig. 1, are carried by the base 21 in the receiving station 27. A crate truck 29 is guided by the tracks 28. The truck 29 carries downwardly extending brackets 30 which in turn support rollers 31 which ride within the tracks 28. This truck is for the purpose of delivering crates to the receiving station 27. One of the crates 33 is shown in the receiving station.

A crate carrying frame 35 is pivotally mounted on a shaft 36 carried by the posts 22 and braces 24. This crate carrying frame 35 is arranged to be moved substantially 180°, that is from the position shown in Fig. 1 to the position shown in Fig. 4. The upper part of the frame 35 is opened so that when the crate is delivered to the position shown in Fig. 4 i. e. in its inverted position, the cans contained in the crate may fall by gravity out of the crate onto an endless belt 38. Belt 38 is mounted on rollers 39 and rotates 50 in a clockwise direction, as viewed in Fig. 4. At

the right end of the endless belt 38 there is provided a slide 41 extending downwardly and to the right, over which the cans slide to another endless conveyor 42 for delivery of the can to an unscrambling machine (not shown). The rollers 39 are generally horizontally disposed with respect to one another and are carried on a frame work 44. This frame work 44 is suitably attached to the braces 24 at the left end and by braces 45 at the right end. The braces 45 are connected to the base 21. The endless belt is preferably driven by an electric motor 46, geared to the shaft 47 of the right roller 39 by pulley and belt connection, the belt being shown at 48. The bearings for shafts 47 are shown at 49.

A door 50 preferably of the flexible and sliding type is carried by the upper end of the frame 35, as viewed in Fig. 1, and it is arranged to prevent the spilling of the cans from the crate while the crate is being moved from the position shown in Fig. 1 to the position shown in Fig. 4. After the crate is moved to the position shown in Fig. 4, the door 50 is moved slowly to the left at such rate that the cans fall from the crate at a rate substantially equal to the rate at which the can unscrambling machine can right the cans.

A slide 51 is positioned adjacent the right end of the door 50, as viewed in Fig. 4, and it is interposed between the bottom of the crate and the conveyor belt 38 to impede the descent of the cans from the crate to the belt 38. This slide 51 is moved to the left as the door 50 is being opened, i. e. being moved to the left.

Referring more in detail to the drawings, the crate carrying frame includes a frame work 53. This frame work includes, as viewed in Fig. 1, a left front post 54, a right front post 55 which are connected at the top by a strip of metal 56. Similar posts 57 and 58 are disposed rearwardly, respectively, of the posts 54 and 55. A rearwardly extending angle iron 59 connects front posts 54 with rear posts 57 and a rearwardly extending angle iron 61 connects the bottom of front post 55 with rear post 58. A rearwardly extending angle iron 62 connects the upper part of posts 54 with post 57 and a rearwardly extending angle iron 63 connects the upper part of posts 55 with rear posts 58. A rectangularly shaped frame 65 is suitably secured to the upper parts of posts 54, 55, 57 and 58, as viewed in Fig. 1. This frame is provided with a circular opening 66 of slightly less diameter than the external diameter of the crate 33. Bail brackets 68, carrying the bail 69 of the crate 33 is adapted to rest upon the ledge or frame 65 when the crate is inverted as shown in Fig. 4.

Referring again to Fig. 1 it will be seen that there is provided two brackets 71 and 72. These brackets extend rearwardly. Bracket 71 is secured to the lower portion of posts 54 and 57 and bracket 72 is supported by posts 55 and 58. These brackets provide shelves 73 and 74 which are arranged to engage the underside or bottom 75 of crate 33 when the frame 35 is swung about pivot 36 from the position shown in Fig. 1. Limit blocks 77 and 78 limit the counter-clockwise movement of the carrier frame 35. It will be observed that when the frame 35 is in its lowermost position, the top of the shelves 73 and 74 lie in a lower plane than the upper plane of the truck 29 so as to provide a clearance between the bottom of the crate 33 and the shelves 73 and 74 when the truck is being moved for inserting or removing a crate. At each, the extreme front and the extreme rear, the carrier frame includes a

U shape frame 80 including downwardly extending legs 81 and 82 and connecting yoke portion 83. These legs 81 and 82 and yoke 83 are suitably secured to the left, right and top sides of frame work 53, as viewed in Fig. 1. The upper right hand portion of each of these frames 80 carries a collar 84 which in turn is secured to the shaft 36.

The shaft 36 extends forwardly of the front frame 80 and rearwardly of the rear frame 80 and a segment gear 85 is secured to the front end of the shaft 36 and a similar gear 86 is secured to the rear end of the shaft 36. These gears 36 are each rotated by racks 87 which are actuated by the plungers 88 of hydraulic jacks 89. The cylinders 90 of the hydraulic jacks 89 are each connected by pivot pin 91 to the brace 25. A roller 93 is interposed between the rear of the rack 87 and the plunger for holding the rack 87 in operative relationship with the gear 86. The rollers may be carried by the post 22. When hydraulic fluid is admitted to the lower ends of the cylinders 90 through the pipes 95, the plungers 88 will be extended causing a clockwise motion to be imparted to the gears 86 which in turn will cause clockwise motion to be imparted to the crate carrying frame 35. The frame upon rotating in a clockwise direction, from the position shown in Fig. 1, will cause the shelves 73 and 74 to lift the crate off of the truck. The frame 35 and the crate carried thereby is moved from the position shown in Fig. 1 to the position shown in Fig. 4 by one complete stroke of the hydraulic jacks. Obviously, to return the frame 35 and the crate from the position shown in Fig. 4 to the position shown in Fig. 1, hydraulic fluid will be admitted through the pipes 97 to force the plunger 88 inwardly, the fluid within the cylinder 90, at this time flowing from the cylinder through the pipe 95.

Any form of flexible door 50 may be employed. However, I prefer to use the form shown in Fig. 10, comprising a plurality of parallelly arranged U shaped strips 99 each of which includes two legs 100 and a yoke portion 101. These yoke portions are preferably flat and each is suitably secured to rubber belting material 103. The strips 99 are suitably spaced from one another by spacers 104, which latter are suitably welded as at 105 to a leg 100 of the strip. It will be understood that the spacers 104 of one strip are not mechanically or otherwise connected with the leg 100 of the next adjacent strip. Suitable bearings may be carried by some or each of the strips 99. These bearings are shown as 106 which is welded to the underside of the yoke 101 of the strip 99. The bearings 106 are for the shafts of rollers 108.

It is to be understood that these bearings and rollers are disposed at the front and rear (as viewed in Figs. 4 and 5) of the door. These rollers ride in and are guided by front and rear tracks 109. The tracks are formed of U-shaped metal which is suitably secured to the crate carrying frame 35. The tracks 109 lie parallel with the frame 65 throughout the width of the frame work 53 and then are curved in the form of an arch as shown at 110.

The extreme right end of the door 50 is provided with front and rear sockets 113 which are arranged to straddle a bar 114 when the crate carrying frame 35 is moved to the position shown in Fig. 4. This bar 114 is utilized to push the door 50 to the left to open the same and pull the door 50 to the right to close the same.

It will be observed that when the crate carrying frame 35 is in the position shown in Fig. 4, the then lower part of the frame work 53 lies between a front wall and a rear wall 116. These walls 116 are secured respectively to the front and rear portions of frame work 44 and form side walls of a bin 117, the lower wall of the bin being formed by the belt 38 and the slide 41.

Each of these walls 116 provides a horizontally extending track 118 disposed between the frame work 53 and the belt 38. These tracks 118 guide rollers 121 carried by a shaft 122. The underside of each of the tracks 118 carry a stationary rack 123, the teeth of which extend downwardly for cooperation with gears 124. The front gear 124 is disposed forwardly of the front wall 116 while the rear gear is disposed rearwardly of the rear wall 116. These gears are secured to a rotating shaft 126, which latter is driven by a pinion 127 secured thereto. Pinion 127 is rotated by a reciprocating rack 128, and this rack is attached to the outer end of a plunger 129 of a hydraulic jack 130. The lower end of the cylinder 131 of the hydraulic jack is pivoted at 132 to a bracket 133 carried by braces 24 and 45. The shafts 122 and 126 extend rearwardly and are supported by a carriage 135. Bar 114 is also carried by the carriage.

The horizontal movement of the carriage 135 is utilized for opening and closing the door 50. Horizontal movement of the carriage 135 is imparted by the hydraulic jack 130, the rollers 121 being guided in the tracks 118.

Let us assume that the door 50 is closed, as shown in Fig. 4 and that the socket 113 spans the bar 114 of the carriage 135, at which time the hydraulic jack will be in extended plunger position and will be at its extreme right position. Now when the plunger 129 is retracted by injecting hydraulic liquid into the upper part of the cylinder 131 through the pipe 137 and permitting the escape of hydraulic fluid through pipe 138, the pinion 127 and the shaft 126 and the gears 124 will be rotated in a clockwise direction, causing these elements to move to the left, by reason of the meshing of gears 124 with the rack 123. The shaft 126 being journaled in the carriage 135 will cause the carriage 135 and bar 114 thereof to be moved to the left. The bar 114 acting on the door 50 will cause the door 50 to be moved to the left whereby the cans can fall from the crate 33. After the door 50 has moved to the left sufficiently to completely uncover the opening 66 in the frame 65, the door opening movement is stopped. The ratio of the gearing and the stroke of the hydraulic jack 130 is such that sufficient movement of the door is assured by a complete stroke of the hydraulic jack. After the crate is emptied, the action of the track 130 is reversed i. e. fluid is admitted through the pipe 138 and permitted to escape through the pipe 137 whereby the plunger will be moved outwardly to return the carriage 135 to the position shown in Fig. 4.

It will be observed that the heretofore mentioned slide 51 for the cans is part of the carriage 135 and therefore moved to the left as the door is being opened. Thus one mechanism is employed for actuating the door and for moving the can slide.

Referring to Fig. 9 it will be seen that a floating arm 140 is carried by the shaft 126. This arm carries a roller 141 which is arranged to engage the rack 123 on the side thereof opposite

the teeth to hold the rack 128 and the pinion 127 in meshing relation.

Referring to Fig. 2, it will be observed that the truck rails or tracks 28 extend on opposite sides 5 of the receiving station 27 whereby the crates can be placed on or removed from the truck from either side of the receiving station. Any suitable mechanism may be employed for moving the truck but I prefer to use hydraulic mechanism, one form of which is shown in Fig. 2 where-in a rack 143 is carried on the bottom side of the truck. This rack is and consequently the truck is moved horizontally by the rotation of a pinion 144 carried by a rotating shaft 145. The shaft 145 is driven by a pinion 146 which is rotated by a rack 147. The rack 147 is actuated by a plunger 148 of the hydraulic jack 149, the cylinder of which is shown at 150. A roller 152 is suitably carried by the base 21 and holds the rack 147 and pinion in operative relation with one another. It will be understood that the shaft 145 is suitably journaled in bearings carried by the base 21.

The operation of the machine is as follows: A 25 crate is removed from the conveyor which leads from the cooker and is placed upon the crate truck, for example on the right of the receiving station 27, as viewed in Fig. 2. The hydraulic jack 149 is then actuated for causing the crate 33 truck to move to the left to bring the crate 33 in proper position in the receiving station 27. At this time the crate carrier frame 35 is in a position 30 shown in Fig. 1 and the carriage 135, for moving door 50, is in the position as shown in Fig. 1. The jacks 89 are then actuated to swing the frame 35 to the position shown in Fig. 4. The notches 113 of the door 50 will slide over the bar 114. At this time the crate 33 is in an inverted position and the cans therein are being 35 supported by the door 50. The jack 130 is then actuated to move the carriage 135 to the left. This causes the door 50 to slide to the left slowly uncovering the opening 66 in the frame 65 and the cans will slide over the slide 51 onto the 40 clockwise moving belt 38. When the cans reach the right end of the belt 38 they will slide over the slide 41 onto another conveyor leading to a can unscrambling machine. The speed of operation of the jack 130 is such that the rate of flow 45 of the cans from the crate 33 is synchronized with the rate at which the unscrambling machine can right the cans. After a full stroke of the plunger 129 of the jack 130, the door 50 will be opened to its fullest extent whereby all cans will 50 have fallen from the crate 33. After the crate 55 is emptied, the jack 130 is actuated in the opposite direction causing the carriage 135 to close the door 50. After the door 50 is closed, the jacks 89 are actuated to retract the plunger 88 which 60 causes the crate carrying frame 35 to be moved from the position shown in Fig. 4 to the position shown in Fig. 1. When in the position of Fig. 1, the empty crate will again rest upon the truck free of the shelves 73 and 74. The truck can 65 then be moved along the track by the hydraulic mechanism and a filled crate brought into the receiving station 27.

Since the truck rails 28 extend on opposite sides 70 of the unloading machine, as viewed in Fig. 2, the stations on opposite sides of the machine or loading station 27 can be used either as loading or unloading stations or both. For example, if the space on the right is used merely as a loading station, during the period of time that the cans 75 are being emptied, the crate truck is retracked

to the position shown in Fig. 2 and a filled crate is then placed on the truck at the right side of the machine. Then the crate truck is moved to the left to bring the filled crate into the receiving station 27, after the empty crate has been returned to the receiving station, the emptied crate will then be on the left side of the machine. Under such circumstances, the left side functions only as an unloading station for empty crates. Obviously the left side can be used as the loading station for the filled crates and the right side as the unloading station for the empty crates.

Two conveyor lines may lead from the cookers to opposite sides of the unloading machine. In that event the filled crate is, for example, loaded onto the crate truck on the right side of the machine and then, when the crate truck is operated to move the filled crate into the receiving station, the empty crate will be on the left side of the machine. This empty crate is then removed and a filled crate is replaced on the left side of the machine and after it is moved by the truck into the receiving station, the empty crate on the right side of the machine is removed.

From the foregoing it will be seen that there has been provided a machine which not only turns the crate upside down but also controls the rate of flow of the cans from the crates. When the cans are handled by the machine herein disclosed, they are never subjected to such severe jarring movement that would cause denting thereof.

While the form of mechanism of the present invention as herein disclosed constitutes a preferred form, it is to be understood that other forms might be adopted, all coming within the scope of the claims which follows.

I claim:

1. Apparatus for unloading a crate of cans, comprising in combination, with a main frame having a station for receiving a crate; a crate carrier frame moveable over the station and having means for engaging the crate for lifting the crate; a door carried by the crate carrier frame for covering the open top of the crate; means for moving the crate carrier frame from the station and for inverting the carrier frame, said carrier frame having means for holding the crate in inverted position; a conveyor below the frame for receiving the cans from the crate as the door is opened; tracks for slideably mounting said door to the crate carrying frame; an inclined ramp extending from the conveyor to an edge of said door and movable with the door upon the opening and closing thereof; and means for progressively moving the door and the ramp across the open top of an inverted crate to controllably discharge cans from the crate to said conveyor.

2. Apparatus for unloading a crate of cans, comprising in combination with a main frame having a station for receiving a crate; a crate carrier frame moveable over the station and having means for engaging the crate for lifting the crate; a door carried by the crate carrier frame for covering the open top of the crate; means for moving the crate carrier frame from the station and for inverting the carrier frame, said carrier frame having means for holding the crate in inverted position; a conveyor below the frame for receiving the cans from the crate as the door is opened; tracks for slideably mounting said door to the crate carrying frame; an inclined ramp extending from the conveyor to an edge of said door and movable with the door upon the opening and closing thereof; and means for progressively moving the door and the ramp across the open top of an inverted crate to controllably discharge cans from the crate to said conveyor.

3. Apparatus for unloading a crate of cans, comprising in combination with a main frame having a station for receiving a crate; a crate carrier frame moveable over the station and having means for engaging the crate for lifting the crate; a door carried by the crate carrier frame for covering the open top of the crate; means for moving the crate carrier frame from the station and for inverting the carrier frame, said carrier frame having means for holding the crate in inverted position; a conveyor below the frame for receiving the cans from the crate as the door is opened; tracks for slideably mounting said door to the crate carrying frame; a second pair of tracks carried by the main frame and positioned parallel to and below the tracks for the door; a carriage moveably carried by said second pair of tracks and adapted to engage the door when the crate carrier frame is in the inverted position; and means for moving the carriage and the door in their respective tracks so that said door is progressively moved across the open top of an inverted crate to controllably discharge cans from the crate to the conveyor.

4. Apparatus for unloading a crate of cans, comprising in combination with a main frame having a station for receiving a crate; a crate carrier frame moveable over the station and having means for engaging the crate for lifting the crate; a door carried by the crate carrier frame for covering the open top of the crate; means for moving the crate carrier frame from the station and for inverting the carrier frame, said carrier frame having means for holding the crate in inverted position; a conveyor below the frame for receiving the cans from the crate as the door is opened; tracks for slideably mounting said door to the crate carrying frame; a second pair of tracks carried by the main frame and positioned parallel to and below the tracks for the door; a carriage moveably carried by said second pair of tracks and adapted to engage the door when the crate carrier frame is in the inverted position; and means for moving the carriage and the door in their respective tracks so that said door is progressively moved across the open top of an inverted crate to controllably discharge cans from the crate to the conveyor.

5. Apparatus for unloading a crate of cans, comprising in combination with a main frame having a station for receiving a crate; a crate carrier frame moveable over the station and having means for engaging the crate for lifting the crate; a door carried by the crate carrier frame for covering the open top of the crate; means for moving the crate carrier frame from the station and for inverting the carrier frame, said carrier frame having means for holding the crate in inverted position; a conveyor below the frame for receiving the cans from the crate as the door is opened; tracks for slideably mounting said door to the crate carrying frame; a second pair of tracks carried by the main frame and positioned parallel to and below the tracks for the door; a carriage moveably carried by said second pair of tracks and adapted to engage the door when the crate carrier frame is in the inverted position; and means carried by the main frame for moving the carriage and the door in their respective tracks so that said door is progressively moved across the open top of an inverted crate to controllably discharge cans from the crate to the conveyor.

6. Apparatus for unloading a crate of cans, comprising in combination with a main frame having a station for receiving a crate; a crate carrier frame moveable over the station and having means for engaging the crate for lifting the crate; a door carried by the crate carrier frame for covering the open top of the crate; means for moving the crate carrier frame from the station and for inverting the carrier frame, said carrier frame having means for holding the crate in inverted position; a conveyor below the frame for receiving the cans from the crate as the door is opened; tracks for slideably mounting said door to the crate carrying frame; a second pair of tracks carried by the main frame and positioned parallel to and below the tracks for the door; a carriage moveably carried by said second pair of tracks and adapted to engage the door when the crate carrier frame is in the inverted position; means for moving the carriage and the door in their respective tracks so that

said door is progressively moved across the open top of an inverted crate to controllably discharge cans from the crate to the conveyor; and an inclined ramp mounted on said carriage and extending from the conveyor to an edge of said door.

6. Apparatus for unloading a crate of cans, comprising in combination with a main frame having a station for receiving a crate; a crate carrier frame moveable over the station and having means for engaging the crate for lifting the crate; a door carried by the crate carrier frame for covering the open top of the crate; a latching element carried by the door at one edge thereof; means for moving the crate carrier frame from the station and for inverting the carrier frame, said carrier frame having means for holding the crate in inverted position; a conveyor below the frame for receiving the cans from the crate as the door is opened; tracks for slideably mounting said door to the crate carrying frame; a second pair of tracks carried by the main frame and positioned parallel to and below the tracks for the door; a carriage moveably carried by said

second pair of tracks; a second latching element mounted on the carriage to engage with said first mentioned latching element carried by the door when the crate carrier frame is in the inverted position; and means for moving the carriage and the door in their respective tracks so that said door is progressively moved across the open top of an inverted crate to controllably discharge cans from the crate to the conveyor.
